ELECTRONIC CIRCUIT

Daniel S. Pensyl, Garden City, N. Y., assignor to
 The Sperry Corporation, a corporation of Delaware

Application October 15, 1943, Serial No. 506,361

4 Claims. (Cl. 178—44)

1

My invention relates generally to electronic circuits, and, more particularly, to electronic switching circuits.

As an object of my invention I wish to provide a gating circuit which will pass a desired signal only, with no part of the gating voltage appearing as a pedestal in the circuit's output.

It is another object of my invention to provide a gating circuit in which the desired signal is reproduced in the output thereof with high gain and without compression of the signal in its low amplitude range.

Another object of my invention is to provide a gating circuit in which the gating voltage is applied to a balancing network interposed between the signal receiving elements thereof and the output terminals in such manner that no component of the gating voltage appears in the output.

As another object of my invention, I wish to provide a method and apparatus for gating a signal which limits the action of the gating voltage employed substantially to that of initiating electron flow.

Still another object of my invention is to provide an electronic circuit comprising a signal channel and a gating voltage channel, both of which are interconnected in such a manner that a double loop circuit is formed, one loop of which provides a bucking voltage equal in magnitude to the fraction of the gating voltage applied to the circuit's switching means, so that the net gating voltage appearing in the output of the circuit is equal to zero.

It is a further object of my invention to provide a gating circuit in which the signal input and output is unbalanced to ground, and in which the signal is gated with a gating voltage through a balanced switching network in such a manner that the value of the gating voltage in the output of the circuit is equal to zero.

Another purpose of my invention is to provide an electronic switching circuit which may be used as a rejection gating circuit.

It is also a purpose of my invention to provide a switching circuit responsive to a gating voltage which, in addition to providing a voltage for operating the switching elements of the circuit, will also supply a biasing voltage thereto.

As another object of my invention, I wish to provide a gating circuit having ungated signal receiving terminals, gated signal output terminals and a switching circuit interposed between the input terminals and output terminals which is responsive to a balanced gating voltage applied

2

in such manner that it does not appear in the output of the circuit.

Other objects of my invention will become apparent as the description proceeds.

5 In carrying out my invention in a preferred embodiment thereof, I provide a circuit upon whose input terminals are impressed ungated signals, among which is the desired signal to be passed. From this point they are delivered to 10 a balanced bridge circuit whose four arms are made up of unilateral current-conducting elements, such as diodes, so as to form a switching circuit. Across one pair of terminals of the bridging circuit is impressed the gating voltage which 15 is received from a pulse transformer in synchronization with the signal which is to be passed by the gating circuit. On the other terminals of the switching circuit are respectively connected the aforementioned signal receiving means and the 20 gated signal output means. The gating voltage appearing across the bridge circuit renders the normally non-conducting unilateral current conducting elements conducting, thereby permitting the passage of the desired signal across the bridge 25 circuit. The switching means being arranged as a balanced bridge balances the gating voltage to ground, and no part of the same appears in the signal output of the gating circuit.

30 In a modification of my invention I provide a similar circuit which employs a plurality of impedance matching devices between which is interposed a single unilateral current conducting device connected to operate as the switching portion of the circuit. A gating voltage is impressed 35 across this device to make it conducting during the period of reception of the desired signal. The gating voltage circuit is so arranged that two loops are formed, one of which supplies a bucking voltage equal to the gating voltage. This 40 limits the action of the gating voltage to that of firing the switching tube and thus prevents it from appearing as any part of the signal which is passed by the gating circuit.

In a third embodiment of my invention I arrange 45 a circuit which, unlike the previous two modifications mentioned, balances the signal to ground. This first function is accomplished by passing the ungated signals through an impedance matching device to the primary winding of 50 a pulse transformer whose secondary is connected to balance the signals to ground. From the secondary winding of the transformer the signals are fed to a plurality of unilateral current conducting elements which are connected for balanced operation and which are responsive to the

gating voltage that renders them conducting for the period of reception of the desired signal. As in the previous two mentioned modifications, the switching elements are so connected that no part of the gating voltage appears in the output of the circuit.

A more comprehensive understanding of my invention will be afforded from the following detailed description when taken together with the accompanying drawing in which like reference numerals have been used throughout to designate like parts, and in which

Figs. 1A and 1B are representative characteristic curves of an electronic valve showing its use as an electronic gate.

Fig. 2 is a schematic circuit diagram of a preferred embodiment of my invention.

Fig. 3 is a schematic circuit diagram showing means for self-biasing the switching elements of the circuit shown in Fig. 2.

Figs. 4 and 5 are circuit diagrams of modified forms of my invention, and

Fig. 6 is a graphic showing of a composite wave form which may be applied conveniently to any of the circuits shown in Figs. 2, 4 or 5 to provide negative bias for the switching elements thereof.

In various applications of ultra high frequency reception, such as that of radio detection and ranging, it is desirable to condition a receiver for passing selected signals only from a group of reflected signals. The circuit which performs this function is referred to in the art as a "gating" circuit, or gate, and is responsive to a voltage of a particular wave form which may be termed as a "gating voltage," also referred to as a "gate." For the purpose of this description, however, the term "gate" will be applied to the circuit which permits the passage of the desired signal, and the term "gating voltage" will be applied to the particular wave form which is used to operate the gate in timed sequence with the received signals so that only the desired signal is passed.

For example, a group of signals such as 11, 12 and 13, illustrated in Fig. 1A, may be received as reflected waves from a particular object which a ranging circuit desires to detect and the signal 12 only is to be selected for passage through its receiver circuit. Thus, a switching circuit must be provided which will "turn on" to pass signal 12 and "turn off" to prevent the passage of all other signals such as 11 and 13. This circuit, as stated before, is called a "gate" since it "opens" for signal 12 to "pass through" and closes to prevent the passage of undesired signals 11 and 13.

In the prior art, it has been common practice to use a single electronic valve, with a plate load resistor, as the gate and to impress upon the control grid thereof a gating voltage which will erase a fixed grid bias, make the valve conducting, and permit a pulse similar to the selected signal to go through. For example, such an electronic device may have a characteristic curve similar to that illustrated in Fig. 1A. Here the signals 11, 12 and 13 are received on the control grid thereof together with the gating voltage 15 which is superimposed. The control grid of the electronic valve is biased beyond cut-off by the fixed bias 16 applied thereto and, as illustrated, the gating voltage pulse 15 is synchronized to arrive with selected signal 12. This, in effect, "elevates" signal 12 to a higher level, and, as signal 14 it swings the grid of the tube positively

to produce a pulse from positive source which is passed through the gate to appear in the output as 14', the gating voltage pulse 15 being sufficient to erase a part of the bias voltage 16 and render the tube conducting.

It will be noted from the figure that such operation forces the gate to pass the signal 14 while operating on the curved portion of its characteristic curve, which reproduces the desired signal in the output circuit with very little, if any, gain, and also forces the signal to be compressed in the range of its low amplitude. In other words linear operation is not obtained.

By changing the value of the fixed bias 16 it is possible to overcome this difficulty and move the operating point of the valve to a point on its characteristic curve wherein the signal 14 will be reproduced as signal 14' with high gain, Fig. 1B.

It will be noted, however, that any bias supplied to the control grid of the electronic valve which will force the same to operate on the linear portion of its characteristic curve will, by necessity, cause a reproduction of a portion of the gating voltage 15 which will appear in the output voltage as a pedestal 16'.

Where it is desired to pass the selected signal having a linear relationship between input and output, with relatively high gain, and without the appearance of pedestals in the circuit output due to the gating voltage, other means must be employed for gating purposes.

These requirements are met by the circuit illustrated in Fig. 2 which is a preferred embodiment of my invention and in which a balanced switching means 31 is employed to pass signals selected from the group of ungated signals received on input terminal 17. Under the influence of a gating voltage which is received on the primary winding of pulse transformer 39, the switching circuit is rendered conducting to pass the desired signals to the impedance matching device 47.

Element 22, illustrated as a triode, is employed for the receiving impedance matching device and receives ungated signals from the input terminal 17 on its grid 21 through the coupling elements comprising the capacitor 18 and the resistor 19. Positive voltage is received on plate 23 of this element, and the cathode 24 thereof is connected to ground through the cathode resistor 25. Element 22 operates as a cathode follower and delivers the signals received on its grid without inversion to input terminal 29 of the balanced bridge circuit 31, through blocking capacitor 27 and resistor 28, the latter providing a direct current return path for the bridge. Balanced switching means 31, which comprises unilateral current conducting elements 32, 33, 34 and 35, is connected to receive a gating voltage on its terminals 36 and 37, from pulse transformer 39. Connected in parallel with the secondary winding 42 of transformer 39 is a balancing potentiometer 43 having a grounded tap 44. This potentiometer improves the operation of the circuit by balancing out capacitances to ground which may be present when transformer 39 is operated over a wide range of frequencies. To further assist in balancing bridge 31, a balancing condenser 30 is coupled between terminal 37 and ground.

In order to prevent the gating voltage transformer 39 from shunting some of the signals received on the input terminals 17 of the circuit

and amplified in element 22, series resistors 45 and 46 are connected in the gating voltage leads to gating circuit 31.

The output of balanced switching circuit 31 is taken from terminal 38 and fed to an impedance matching circuit including electron discharge device 47 through the coupling elements 48 and 52 to grid 51 thereof. Positive energy is supplied plate 53, and cathode 54 is connected to ground through cathode load resistor 55. Resistor 49, similar to resistor 28, also performs the function of a low level impedance device at the output of bridge 31. The output of the circuit is taken from the cathode 54 at junction point 56 and delivered to the output terminal 57.

Discrimination of the bridge circuit 31 against undesired pulses such as 11 and 13 in Fig. 1 depends on plate-to-cathode capacities of the unilateral current conducting elements 32, 33, 34 and 35 and also on the bias potential of these elements when no gating voltage is supplied through transformer 39. Accordingly, for the purposes of discrimination control, means for introducing self-bias to these elements is provided by shunt resistance-capacitance portions 58, 59 and 61, 62 in the circuit illustrated in Fig. 3, which may be substituted for the circuit portion of Fig. 2 shown above the line $a-a$. In this alternative circuit the gating voltage is supplied to the bridge 31 in identically the same manner as explained in connection with the circuit illustrated in Fig. 2 with the exception that the R.-C. combinations comprising the capacitor 58 and the resistor 59, and the resistor 61 and the capacitor 62, are interposed respectively in the leads serving terminals 37 and 36, respectively, of the bridge circuit 31.

In operation, the unilateral current conducting elements 32, 33, 34, and 35, comprising the four arms of the gate 31, are normally cut off. Under the influence of a gating voltage which is received on the terminals of primary winding 41 of transformer 39 and is of such polarity that terminal 36 of the bridge 31 is made positive with respect to terminal 37 thereof, all four of these elements are rendered conducting and thus they become effective as resistances for the duration of the gating pulse. During the time that the elements 32, 33, 34 and 35 are conductive, the point 38 of the balanced bridge assumes the same potential as that of point 29, and voltage variations with respect to ground at point 29 are reproduced at point 38. Further, since the gating voltage is balanced to ground, no portion thereof will be passed from the switching circuit 31 to appear as a part of the gated signal on the output terminal 57.

In the brief interval during which junction 36 is maintained positive with respect to junction point 37 by the gating voltage supplied through transformer 39, unidirectional current flow is maintained through the two paths including series diodes 32 and 34 and series diodes 33 and 35. During this interval, a small potential change, positive or negative, at point 29 results in potential changes in the same direction at points 36 and 37, and thus in a potential change in the same direction at the bridge output point 38. Thus, as suggested in the above paragraph, the elements 32, 33, 34 and 35 are not employed in the circuit as unidirectionally conductive devices, but instead are so biased as to be non-conductive as point 36 is made slightly negative with respect to point 37, or effectively bi-directionally conductive as point 36 is made greatly positive with respect to point 37, in accordance with the

gating voltage variations supplied through transformer 39.

In this arrangement, the impedance matching electronic elements 22 and 47 may be useful for operation as a video gating circuit. The former element performs the function of reducing the effects of stray capacitances and distributed constants of the source and minimizes their effectiveness by operating at a low impedance level. 5 The cathode follower impedance transformer 22 may therefore be omitted from the circuit when the impedance requirements looking into the input terminals of the circuit are of such nature that its use is unwarranted. Similarly, the cathode follower 47 may be omitted from the circuit, if the application is such that a high-impedance load is presented to the output of the bridge 31. 10 Just as the circuit may be operated to gate a selected signal, it may also be operated as a rejection gate to suppress a selected signal or group of signals. To operate the circuit as a rejection gate simply requires a reversal of the polarity of the gating voltage applied by transformer 39 to the terminals 36 and 37. 15 In the modification of my invention illustrated in Fig. 4, I employ a cathode follower illustrated as 22, similar to the input cathode follower in the circuit shown in Fig. 2. The output of this element is taken from the point 26 and delivered 20 to the cathode 64 of a unilateral current conducting element 63 which is illustrated as a diode. From the plate 65 of this element a signal received from point 26 is passed to the cathode coupled stage 74, illustrated as a triode, which has its grid 30 grounded as shown. Positive voltage is supplied to plate 75, and the output of the circuit is taken from cathode 73 thereof at point 72. A gating voltage which is supplied to the primary winding 71 of transformer 69 induces in 35 secondary winding 68 a voltage having the polarity shown. This voltage is impressed across the switching element 63 through the resistors 66 and 67. A balancing resistor 70 is connected to ground from point 69 as shown. In this manner the gating voltage induced in secondary winding 68 of transformer 69 is conducted through two loops, one of which is traceable through secondary winding 68, thence through resistor 67 and the non-linear switching element 63, thence 40 through resistor 66 and back to the secondary winding. The second loop is traceable through the secondary winding 68 of transformer 69, across the resistor 70 to ground, thence from ground through a parallel combination of the cathode resistor 25 and the plate-to-cathode resistance of tube 22, then through the resistor 66 45 and back to the secondary winding of the pulse transformer. The values of the circuit parameters within these loops are not critical, but for correct operation the resistors 66 and 70 should be so chosen that the gating voltage in the two loops will be balanced to prevent any part thereof from appearing in the output signal at point 55 72. 50

The operation of this circuit, as may be inferred from its description, is as follows. The gating voltage impressed across the switching element 63 renders the same conductive for the period of the gating voltage and thereby permits 60 the passage of the signal received on input terminal 11 to the output terminal 72 of the circuit. The portion of the gating voltage which is traceable through the secondary winding 68 of pulse transformer 69, resistor 70, ground, resistor 25 and element 22 and back through the

resistor 66, is through the balancing arrangement of resistors 66 and 70, equal to the gating voltage through the loop, comprising the secondary winding of the pulse transformer 71, the resistor 67, the switching element 63, and the resistor 66. Accordingly, the potential of the gating voltage is balanced to ground at the point 72 and does not appear in the output of the circuit as any portion of the signal.

In this embodiment of my invention, the element 63, during relatively long periods, is so biased by the output voltage of transformer 69 that the anode 65 is maintained negative with respect to cathode 64. During these periods, a small potential variation at junction point 26 results in no appreciable potential variation at the anode 65 and point 72. During the relatively brief gate conduction intervals, however, the anode 65 is maintained positive with respect to cathode 64, in accordance with the polarity symbols shown in Fig. 4. During these intervals, any slight potential variation, positive or negative, produced at junction point 26 through the action of element 22, is transmitted through the element 63 to the output junction point 72.

A careful study of the circuit of Fig. 4 reveals that the non-linear resistance element 63 and the resistor 67 form two series-connected legs of a bridge circuit between terminals 26 and 69, while resistors 25 and 70 are two further series-connected legs of the bridge between these terminals. The gating transformer 69, connected in series with resistor 66, is provided for applying controlling voltage pulses between terminals 69 and 26, in accordance with which the resistance of the non-linear resistance element 63 is varied abruptly from a nearly infinite value to a relatively small resistance.

During periods of application of the gating voltage of polarity as shown in Fig. 4, the element 63 is highly conductive and signal voltage applied across resistor 25 produces an output voltage between the junction of elements 63 and 67 and the grounded junction of resistors 25 and 70. The gating voltage applied between the opposite junction points or terminals 26 and 69 produces substantially equal voltage drops across resistors 67 and 70, so that substantially no potential difference is produced between terminal 72 and ground due to the gating voltage applications.

In the embodiment of my invention illustrated in Fig. 5, the ungated signals are impressed upon the grid 79 of electronic discharge device 78, whose plate 81 receives positive voltage and whose cathode 82 is connected to pass the signals received on the grid 79 of this element through the coupling elements comprising the resistor 83 and capacitor 84 to the primary winding 85 of the transformer 86. A secondary winding 106 of transformer 86 is balanced to ground through the resistors 104 and 105, whose center point 102 is connected as shown. The balanced output of the secondary winding is delivered to cathodes 107 and 108, respectively, of switching elements 87 and 88. Bias is applied to these electrodes from source 101. The output of each of the switching elements 87 and 88 is taken respectively from the plates 89 and 91 thereof and delivered across the shunt resistor 95 to the primary winding 92 of pulse transformer 93. A pulse transformer 98 is connected to induce a gating voltage in the secondary winding 97 thereof, which is connected in series with the biasing source 101. This voltage is impressed upon plates 89 and 91

of the switching elements 87 and 88, respectively, producing equal currents through these elements and through plate resistors 96 and 98. The output of the circuit is taken from output terminal 109 through transformer 93.

The ungated signals received on grid 79 of element 78 are induced in the secondary winding 106 of pulse transformer 86, wherein they are balanced to ground as shown. The switching elements 87 and 88, which are biased from a source 101, are normally non-conducting but are rendered conducting under the influence of the gating voltage received on the terminals of primary winding 99 of pulse transformer 98. From this point the polarity of the gating voltage is as indicated, which, through the plate resistors 96 and 98, applies a positive voltage to the plates 89 and 91, respectively, of the switching elements 87 and 88. This renders these elements conducting for the duration of the gating pulse to thereby permit the passage of a selected signal which is received in synchronization therewith. When tubes 87 and 88 are rendered conducting, the signal which is balanced to ground as aforementioned appears with opposite polarity on the cathodes 107 and 108 of tubes 87 and 88. In this manner the signal is additive to the gating voltage flowing in one half of the balanced switching circuit and subtractive in the other half. This produces a potential difference across the resistor 95 which in turn is induced in the secondary winding 94 of pulse transformer 93, and passed to the output terminal 109 as the desired signal. The gating voltage, being balanced out in the two switching loops, does not appear in the output.

As previously mentioned in connection with the modification of my invention shown in Fig. 2, it is possible to operate it as a "band" rejection circuit by simply reversing the polarity of the gating voltage impressed on the switching circuit 31. The circuits illustrated in Figs. 4 and 5 may also be operated as band rejection circuits by choosing the circuit parameters to apply proper bias to the switching elements thereof.

In the embodiments of my invention illustrated, I have used a pulse transformer to change from a balanced to an unbalanced circuit. It is to be understood, however, that balanced circuits employing the use of tubes may be employed also. The pulse transformer has the advantage of requiring no operating voltage and is simple to install.

As stated before, the impedance matching transformers, illustrated in Fig. 2 as elements 22 and 47 and in Fig. 3 as elements 22 and 74, may be omitted, depending upon the requirements of the circuit.

In each of the embodiments of my invention illustrated, it is possible that, due to the inherent characteristics of the switching elements used, a small signal voltage may be passed through the gating branches of the circuit when the tubes are normally non-conducting. If this action is objectionable, the switching elements of each circuit may be conveniently biased by substituting a gating voltage of the wave form illustrated in Fig. 6. Here a wide negative gating voltage of the form illustrated as 115 is mixed with a narrow positive gating voltage 116 to form a composite wave 117.

When the gating voltage 117 is applied to the switching elements of any of the circuits illustrated, the switching elements will be biased beyond cut-off for periods represented by the por-

tions of gating voltage 117 which are designated by the numerals 118 and 119, and the tubes will conduct for only such period of time as the portion of the gating voltage 117 produced by the narrow gating voltage 116 is applied.

Other modifications of my invention are, of course, possible, and they may present themselves in view of the foregoing disclosure. Accordingly, the recitations and representations herein made are to be considered as illustrative and in no wise in a restrictive sense, and the spirit and scope of my invention is to be considered of such breadth as described by the appended claims.

What is claimed is:

1. Bridge circuit apparatus for selectively coupling a source to a load and for controlling energy transfer therebetween in accordance with a control voltage, comprising a non-linear resistance element and a first linear resistance element connected in series between opposite junction points and forming a first intermediate junction therebetween, two further linear resistance elements connected in series between said opposite junction points and forming a second intermediate junction therebetween, means for intermittently applying a control voltage between said opposite junction points for effecting changed conductivity of said non-linear element during said voltage applications, means for coupling a signal source to the terminals of one of said elements, and means for connecting a load between said intermediate junctions.

2. A bridge circuit comprising a non-linear resistance element and a first linear resistance element connected in series between opposite junction points, second and third linear resistance elements connected in series between said junction points, said second linear resistance element being connected to said non-linear resistance element at one of said junction points and said third linear resistance element being connected to said first linear resistance element at the other of said junction points, means for applying a signal voltage across said second linear resistance element, utilization circuit means connected between the junction of said non-linear element and said first linear element and the junction of said second and third linear elements for utilization of the signal voltage coupled thereto through said non-linear element, and means for applying a controlling voltage between said opposite junction points for abruptly varying the resistance of said non-linear element.

3. A controllable signal transmission circuit comprising a non-linear resistance element characterized by appreciable variation of conductivity in accordance with voltage impressed thereon, a first resistor connected in series with said element, control means connected to said series-connected element and first resistor for applying thereto a gating voltage producing a voltage drop

component across said first resistor and causing appreciable variation of conductivity of said element, neutralizing voltage drop means connected to said control means and including a second resistor connected at one end to the junction of said control means and said first resistor for producing a gating voltage drop component across said second resistor substantially equal to the gating voltage drop component across said first resistor, current path means being provided between the end of said second resistor opposite said one end and the junction of said control means and said non-linear resistance element, means for applying an input signal between said non-linear resistance element and said second resistor for conduction therethrough during periods of high conductivity of said element, and signal output utilization means connected to said first and second resistors at points thereon non-adjacent to the connection of said resistors to said control means, whereby a version of said input signal is applied to said utilization means during periods of high conductivity of said non-linear resistance element and gating voltage drop components in said first and second resistors are effectively neutralized.

4. Apparatus for selectively controlled coupling between a signal source and a signal utilization device, comprising an electrical signal source having first and second terminals, a two-terminal utilization device for receiving a version of said signal voltage during selected time intervals, one terminal of said utilization means being connected to said first source terminal, a non-linear impedance element connected between the other terminal of said utilization device and said second source terminal, a pair of impedance elements connected in series between the terminals of said utilization device and forming an intermediate junction therebetween, and means connected between said intermediate junction and one of said source terminals for applying a control voltage to said non-linear resistance element whereby the conductivity thereof may be varied electrically.
